UNITED STATES PATENT OFFICE.

EDWARD SCHUYLER, OF SYRACUSE, NEW YORK.

SHOE-SHINING CHAIR.

Application filed July 21, 1923. Serial No. 653,002.

To all whom it may concern:

Be it known that I, EDWARD SCHUYLER, a citizen of the United States, residing at Syracuse, in the county of Onondaga and 5 State of New York, have invented certain new and useful Improvements in Shoe-Shining Chairs, of which the following is a specification.

This invention relates to improvements 10 in chairs, and has for its object to provide an adjustable chair for use by shoe-shiners, which may be approached and occupied by a person the same as any ordinary chair, without requiring him to climb upon an 15 elevated platform in order to reach the chair. A further object is to provide a chair of the class, which is normally disposed substantially at the floor level, and whose seat, while the chair awaits occu- 20 pancy, is spaced the usual distance from the floor, the arrangement of the chair being such that the patron walks directly to and sits down in the chair, and places his feet upon a floor-level foot-rest, after which the 25 chair together with the occupant is raised, until the occupant's feet are spaced the right distance from the floor for conveniently performing the polishing work. A further object is to provide novel means 30 for adjusting the foot-rest to suit persons of different stature. A further object is to provide novel and powerful mechanism for elevating and lowering the movable parts of the chair. And a further ob- 35 ject is to provide means for supporting and guiding the movable chair.

I attain these objects by the means set forth in the detailed description which follows, and as illustrated by the accompany- 40 ing drawings, in which—

Figure 1 is a top-plan view of the complete device. Fig. 2 is a side elevation of the same; showing the adjustable nature of the device. Fig. 3 is a detail view of 45 the adjustable foot-rest. Fig. 4 is respectively a top-plan and a side elevation of the elevating member carried by the chair proper. Fig. 5 is a rear side elevation of the device. Fig. 6 is respectively a top 50 and a side view of one of the brackets that support the elevating screw. And Fig. 7 is respectively a top and a side view of one of the lugs by which the chair is guided.

In the drawings, 2 represents the relatively broad flat base, which may rest per-

manently on the floor 2'. 3-3 represent similar posts, which rise from the rear corners of the base to which they are rigid, the said posts being held at right angles to the base by angular braces 3', as shown in Figs. 1, 2 and 5, and the tops of the posts being tied and held parallel to each other by a bar 3".

The chair proper, as A, consists of a relatively thin flat platform 4, which parallels and rests upon the base 2, when the chair is in its lowermost position, shown by the full lines in Figs. 2 and 5. 5 is the horizontal seat, which is spaced the usual distance above the platform 4, and is supported by similar open side members 6-6', the latter rising from the platform and being tied together by the seat 5, and by a back 7 which parallels the posts 3, and extends from the seat to the tops of the sides. The inner faces of the sides are formed with arm-rests 6". The seat 5 is supported midway between the sides 6, by an upright part 8, which is rigid to the seat and platform. The chair A is movable vertically, and is guided during such movements, by similar lugs or parts 9, which are secured to the back 7 and have arc-shaped portions 9', that slidably embrace the posts 3. The forward end of the seat 5 is braced by an inclined post 10, which rises from the platform 4 and aligns with the support 8. 12 represents the foot-rest, which is bored out near its middle to loosely receive the post 10, upon which it is adjustable, as shown in Fig. 3, for properly supporting the feet of persons of different stature. The forward end of the part 12 comprises a relatively broad fork, upon the arms 12' of which the feet rest during the polishing operations, the said arms being provided with depressions 12", which receive the shoe-heels. The rear end of the part 12 is formed with a narrow fork 12", that loosely straddles the support 8 which co-operates with the post 10, for guiding the foot-rest during its vertical movements. The part 12 is normally supported on the platform 4, and when it is moved and set in the various positions, it is held from accidental movement by the slight canting or tilting of said part, as shown by dotted lines in Fig. 3. This temporary locking of the foot-rest in the adjusted positions, may be effected by the

100
105
110

weight, supplemented by a slight downward pressure, of the feet upon the arms 12', which cause the binding of the body 12 against the front and rear surfaces of the post 10, in a well-known manner.

The chair A may be raised and lowered while the occupant is sitting in it, as shown by the full and dotted lines in Figs. 2 and 5, by any suitable means and power, as for example, a screw 13, which extends vertically parallel to the back 7, and a nut 14, which may be an integral part of an angular bracket comprising a horizontal arm 14' that is secured to the seat 5, and a vertical arm 14", which is secured to the back 7, by screws 14^b. The top end of the screw 13 has its bearing in a guard 15, which is rigidly secured to the rear faces of the posts 3, while the lower end of said screw is operatively supported by a bracket 13', which is secured to the base 2, by screws 18^a. The screw 13 supports a relatively large worm-gear 16, which is driven by a worm 17, the latter being mounted on a shaft 17', which is journaled in brackets 18-19, the said brackets being secured to the base, by screws 18'. One end of shaft 17' is fitted with a miter-gear 20, which may be driven by a similar gear 20', the latter being mounted on and operated by a shaft 21, which is supported by the bracket 19, and by a bearing 3^b carried by one of the braces 3'. The free end of shaft 21 is provided with a crank 21', by which the elevating mechanism may be manually operated. Obviously, the shaft 17' may be driven by a motor, or by any other suitable power (not shown).

At the start of the shoe-shining operation, the customer walks directly to the chair A while the latter is in its lowermost position, shown in Fig. 2, and sits down on the seat 5 and places his feet upon the foot-rest 12. The operator then turns the crank 21' in the direction for elevating the chair together with the occupant, as shown by the dotted lines in Figs. 2 and 5. This positions the occupant's feet at the right height from the floor for conveniently performing the shining work. When the work is finished, the operator turns the crank 21' in the opposite direction for lowering the chair to the starting point. The chair may then be vacated like any ordinary chair that rests on the floor.

Having thus described my invention, what I claim is—

1. The combination with a fixed base and posts rising from the rear corners thereof, of a chair movable relatively to said posts comprising a platform, a seat above said platform, a back rising from the seat and guided by said posts, and an elevating mechanism for raising and lowering said chair.

2. The combination with a fixed base and posts rising from said base, of a chair mov-

able relatively to said posts comprising a platform, a seat above said platform, a back rising from the seat and guided by the posts, an elevating mechanism comprising a nut carried by said chair and a screw operatively supported by said base, and a worm-and-gear mechanism for operating said screw.

3. The combination with a fixed base and posts rising from the rear corners thereof, of a vertically movable chair comprising a platform, a seat supported above the platform, a back rising from the seat parallel to said posts, means carried by said back and engaging said posts for guiding the chair, and an elevating mechanism comprising a nut carried by the chair and a screw and worm-gear carried by said base.

4. In a chair, the combination with a fixed base and posts supported by the base, of a platform normally mounted on the base, a seat above said platform, side members to support the seat rising from the platform, a back connecting said side members, guide-lugs carried by said back and engaging said posts, a screw operatively supported by the base, a nut fixed to said back engaged by said screw, a worm-and-gear mechanism for operating said screw and miter-gears for driving said mechanism.

5. The combination with a fixed base, of a chair mounted for vertical movement on said base including a platform, a seat, side members spaced by and supporting said seat, a mechanism for raising and lowering said chair comprising a nut carried by said seat and a screw operatively supported by said base, a worm-and-gear mechanism for operating said screw, and means for driving the latter mechanism.

6. The combination with a stationary base, of a chair mounted for vertical movements upon said base, including a platform normally resting on the base, a seat spaced above the platform parallel thereto, a back rising from the rear end of the seat, an inclined post rising from the platform to the seat, a support alining with said post, a foot-rest slideable on said post and said support adapted to be adjusted and held in different positions relatively to the seat and platform by the canting of said rest, a screw for elevating and lowering said chair, and a mechanism for operating said screw.

7. A shoe-shining chair, comprising a fixed base, posts rising from the rear corners of the base, a seat spaced above said base, a back rising from said seat parallel to said posts, side members supporting and spacing said seat and said back, means for raising said seat for positioning the occupant's feet for conveniently performing the polishing work and for lowering said seat after said work is done, an inclined post extending below the seat, and a foot-rest adjustable vertically on said post relatively to the seat.

8. A shoe-shining chair, comprising a platform, a seat spaced above said platform, an inclined post rising from the platform and supporting said seat, a back extending upwardly from the seat, a foot-rest adjustable on the inclined post, a base fixed beneath said platform, posts rising from said
- base parallel to said back, an elevating screw disposed between said posts and engaging parts carried by said back for raising and lowering said chair, and a mechanism for operating said screw.

In testimony whereof I affix my signature.

EDWARD SCHUYLER.
